US0D1106289S

(12) **United States Design Patent** (10) **Patent No.:** **US D1,106,289 S**
(45) **Date of Patent:** **** Dec. 16, 2025**

(54) **ELECTRIC DISCHARGE MACHINE**

(71) Applicant: **SHENZHEN SMARTSAFE TECH CO., LTD.**, Shenzhen (CN)

(72) Inventors: **Jun Liu**, Shenzhen (CN); **Shaoli Gu**, Shenzhen (CN)

(73) Assignee: **SHENZHEN SMARTSAFE TECH CO., LTD.**, Shenzhen (CN)

(**) Term: **15 Years**

(21) Appl. No.: **29/944,007**

(22) Filed: **May 24, 2024**

(30) **Foreign Application Priority Data**

Nov. 27, 2023 (CN) 202330777671.9

(51) **LOC (15) Cl.** **15-09**

(52) **U.S. Cl.**

USPC **D15/127**; D13/103

(58) **Field of Classification Search**

USPC D13/101, 103; D15/122, 127, 144, D15/144.1, 144.2, 199

CPC B23H 1/00; B23H 1/02; B23H 1/022

See application file for complete search history.

(57) **CLAIM**

The ornamental design for an electric discharge machine, as shown and described.

DESCRIPTION

FIG. 1 is a front, right and top perspective view of an electric discharge machine, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the electric discharge machine that form no part of the claimed design.

1 Claim, 8 Drawing Sheets
